CLAIM

The ornamental design for a rectangle shaped vacuum pouch, as shown and described.

DESCRIPTION

FIG. 1 is a top perspective view of a rectangle shaped vacuum pouch showing our new design;

FIG. 2 is a top view of the design shown in FIG. 1, wherein the bottom view is a mirror image thereof;

FIG. 3 is a front view of the design shown in FIG. 1;

FIG. 4 is a rear view of the design in shown in FIG. 1; and,

FIG. 5 is a right side view of the design in shown in FIG. 1, wherein the left side view is a mirror image thereof.
